UNITED STATES PATENT OFFICE.

HELEN J. CUMMINGS, OF CLEVELAND, OHIO, ASSIGNOR TO THE MILLER COMPANY, OF MERIDEN, CONNECTICUT, A CORPORATION OF CONNECTICUT.

DESIGN FOR A GLASS GLOBE.

Application filed October 2, 1926. Serial No. 19,230. Term of patent 8½ years.

To all whom it may concern:

Be it known that I, HELEN J. CUMMINGS, a citizen of the United States, residing in Cleveland, in the county of Cuyahoga and State of Ohio, have invented a new, original, and ornamental Design for Glass Globe, of which the following is a specification, reference being had to the accompanying drawing, forming a part thereof.

The figure is a perspective view of the glass globe made according to my design.

I claim:

The ornamental design for a glass globe, as shown.

HELEN J. CUMMINGS.
